ELECTRICAL COLOR SELECTING DEVICE
FOR WEAVING LOOMS

Kurt Schwabe, Bielitz-Bielsko, Poland

Application December 28, 1936, Serial No. 117,998
In Germany February 2, 1935

4 Claims. (Cl. 139—232)

Electrical bobbin feeler or color selecting devices for weaving looms wherein the shuttle or bobbin is automatically exchanged, are known in which a circuit effecting the exchange of shuttle or bobbin is closed by a weft detector shuttle by the intermediary of circuit closing rails arranged on the shuttle box for closing the circuit.

In these devices the color is often selected mechanically, for instance, by parallel displacement of the cylindrical shuttle exchange box. Such a device may be suitable for looms using shuttles with two different colors but is inappropriate if more colors are used. In addition, owing to the necessarily complicated construction the use of mechanical regulating means easily leads to wrong connections.

When using two shuttles of different colors, it is further known to select electrically the bobbin holder or magazine carried by a pivotal lever and containing spare bobbins, and to bring said holder into the exchange position by arranging in a different manner the circuit closing members which act when the bobbins have run empty. The rotation of the entire holder containing the spares however, is comparatively slow and can only be effected in slow running looms. In another shuttle exchange device for looms having exchange of shuttle the issue of a new shuttle is effected by closing an electric circuit from a pattern device in connection with electrical weft detector or feeler shuttles. Since the shuttle selecting device is operated through the pattern device the arrangement is rather complicated and interruptions occur easily particularly since the exchange circuit is usually only closed so long as the empty shuttle is in the shuttle box. However, it is also known to provide electrical locking or stopping devices (relays) in the circuit of the weft detector or feeler in order to keep the circuits closed for a certain period of time in excess of the duration of the time the shuttle remains in the shuttle box, which circuit regulates the exchange of the shuttle or bobbin and if required, effects an exchange only after several further shuttle picks.

In order to ascertain when a shuttle has run empty a feeler provided with electrical contact pins has been arranged in the shuttle in order to close a circuit dependent on the pattern device and thereby to effect the exchange of shuttle when the bobbin has run empty. A reliable working of this device can hardly be expected as a consequence of the use of a feeler inserted in the shuttle from outside since the time left for closing the circuit is exceedingly small.

According to the present invention there is pro-

vided an electric weft-selecting device for automatic weft-replenishing looms employing shuttles embodying weft feelers, characterized in that in addition to a contact for closing a weft feeler circuit actuating the replenishing mechanism, there are furnished on at least some shuttles additional contacts for closing other circuits for selectively controlling the magazine actuating means, and so arranged in relation to the weft feeler circuit that by the exhausted bobbin through a weft feeler, none, one or more of the selecting circuits are closed, depending upon to which group of the shuttles employed, the shuttle containing the exhausted bobbin belongs, whereby on initiation of the bobbin changing operation there results the positioning under the transfer hammer of a new bobbin of corresponding color or character to the exhausted one, circuit closing rails arranged on and moving with the drop boxes being used which cooperate with stationary current collectors. One or several regulating motors are preferably provided in this construction for driving the bobbin magazines, the switches of which are closed by the intermediary of relays arranged in the feeler controlled circuits when these are closed.

Stop rods or notched bars may also be provided for driving the magazine which stop rods upon closing the feeler circuit or circuits are brought into engagement with knives actuated by one of the loom shafts to bring the magazine into the position required for the exchange operation.

Two magnets (solenoids), for instance, may be provided for moving the four-part bobbin magazine which magnets, when a bobbin has run empty, are excited as required, in accordance with the color of the shuttle or bobbin and co-act in such a manner that after the driving members have altered the position of the shuttle or bobbin holders, four different positions of the latter may be obtained according to whether one or other, both or neither of the two magnets are excited.

By reason of the fact that in the device according to the invention the application of mechanical regulating means is extensively avoided, great reliability in the regulation can be obtained since in electrical regulating means the step by step movement of the mechanical means as well as the oscillation and strong wear and tear of the regulating means, which cannot be avoided in machines running at high speeds, are eliminated. The insertion of interruptors further gives a greater liberty in the application of the device since there is far less limitation as regards the movement of commencing the exchange of bob-

bin than if mechanical regulating means were employed. The whole arrangement is moreover more open and more accessible.

A number of constructional forms of the device according to the invention are illustrated in the accompanying drawings, wherein—

Fig. 1 shows a shuttle box having a number of compartments in side elevation and partly in perspective.

Figs. 2-15 show diagrammatic connections for 10 different constructions of the feeler selecting device.

In the form shown in Fig. 1 the loom has on the feeler side a shuttle box 19 having a number of compartments. Each compartment is provided with a grounded spring 20 to engage a contact plate 5 on the shuttle. Each shuttle is provided with a weft feeler which in known manner causes electric connection between it and the contact plate 5 when the weft in the shuttle is substantially exhausted. Further, a contact strip 18 is provided in each compartment for closing the circuit, the said strip being connected to the metal rail 24, which is mounted on a strip 23 secured to the shuttle box and made of insulating tape. The rail 24 is made in sections insulated from one another, one section for each compartment of the shuttle body. The current collector 25 arranged level with the path of the shuttle to be picked bears resiliently against the metal rail 24 so that only that shuttle can be supplied with current which is level with the path of the picker and is active, that is to say, is about to be picked across the lay. The magnet 22 (Figs. 2-3-5) on the one hand is connected to the collector 25 and on the other hand to the pole R for the source of current of the weft feeler circuit.

Before the current reaches ground in the direction RT it passes through an interrupter mounted on the loom crank shaft or another shaft rotating in unison with the said crank shaft and having for its object to prevent the closing of the current to the shuttle and the commencement of the exchange of bobbin at an undesired instant. This interrupter, for instance, comprises two current collectors 26 and 27 which bear resiliently against a drum 28 made of insulating material. Said drum carries a strip of metal 29 which is sufficiently wide to be in contact with the two current collectors 26 and 27 at the same time and exactly as long as is required to supply the magnet 22 with current. The moment of contact and thus the moment for the commencement of the exchange of bobbin depends on the position of the metal strip 29 relative to the crank of the crank shaft. The current collector 27 is grounded so that the circuit is closed except the contact in the shuttle and the interrupter.

If a shuttle in the box 19 on a level with the picker on the feeler side has a bobbin run empty or nearly so, the circuit is closed from the grounded plate 20 through the plate 5, the feeler F, the plate 18 and rail 24, the collector 25, the electromagnet 22, the source of current RT and so back to the ground with the exception of the interrupter and the magnet is excited at the same instant that the interrupter effects the last contact. The movement of the armature in the magnet 22 can now be used in known manner to start the exchange of the bobbin or shuttle. In this arrangement, however, certain locking or stopping devices are required for the armature of the magnet since the excitement of the magnet never lasts longer than the time which the

shuttle stays in the compartment of the shuttle box. At the same moment, when the shuttle leaves the compartment upon commencement of a pick, the magnet returns to its position of rest.

If the mechanical stopping or locking devices are to be eliminated and if it is intended to obtain an electrical action lasting longer than the time which the shuttle rests in the compartment, the contact rail 25 is suitably connected to a contact surface 30 (Fig. 3) and a blade spring 31 is provided which is lifted by the armature of the magnet 22, so that the contact 32 provided on said spring, bears against the other contact surface 30. The blade spring 31 is mounted on a stationary member 33 and is grounded. If the magnet 22 is excited, the rising armature closes the circuit at 30 and the shuttle can now leave the compartment without hindrance and without the return of the armature of the magnet since the contact remains closed through the medium of the blade spring 31 so long as the current can also pass through the interrupter.

By means of the interrupter the magnet 22 can be supplied with current as long as required and further by the raised position of the armature, regulating movements can be obtained and the action can be extended over a longer period of time. In this way, for instance, by means of the magnet 22 (Fig. 4) the motor M (Fig. 4) can be switched on, which motor may be a three-phase current motor and may be fed from a source of current RST. In this arrangement the phases T and S only pass over the contact surfaces 34 and 35 against which bear the springs 36 and 37 when the armature of the magnet 22 is raised. The springs 36 and 37 are secured at 38 and 39 respectively and from there are connected to the motor. When the magnet is excited the armature is lifted and closes the contact at 30 and at the same time the contacts at 34 and 35 since its movement is at the same time transmitted to the springs 36 and 37 through the medium of the insulated members 40 and 41. The motor M is now fed with current as long as the interrupter is closed. When the metal strip 29 provided on the insulated drum 28 leaves the collectors 26 and 27, the magnet instantaneously falls back to its initial position and at the same time the springs 36 and 37 leave the contacts 34 and 35 and the motor is switched off.

If the duration of the effect of the magnet 22 is intended to be rendered independent of the interrupter U1 (Fig. 5) mounted on the crank shaft, a second interrupter U2, for instance, may be provided on the circuit closing shaft or on the shaft of the motor which effects the exchange of bobbin and connection may be arranged as shown in Fig. 5. In this arrangement the interrupter U1 determines the moment and the commencement of the excitation whilst U2 on the other hand determines the duration thereof.

Instead of the single source of current RT, two sources R1, T1 and R2, T2 (Fig. 6) having two windings N1 and N2 may be provided for the magnet 22 and two interrupters U1 and U2, whereby, for instance, the current R2, T2 may be of higher tension than the current R1, T1 so that it is possible to obtain stronger effects with the current R2, T2 than with R1, T1. Similarly to the first-mentioned arrangements, stopping or locking devices are provided for the magnet which comprise the contact surfaces 30 and 33, the blade spring 31 as well as magnet 41. Obviously in the arrangement shown in Fig. 6, a motor can be switched on

by the magnet 22, as described with reference to Fig. 4.

The feeler device described has the advantage over the devices heretofore used wherein needles or other means were inserted in the shuttle for the purpose of closing the contact, that no important distance has to be covered in order to close the contact. The time saved in this way increases the security of the selecting since magnets respond all the better, the longer they are energized. As well known in multiple box looms or check looms the interval between the finish of the exchange of the bobbin or shuttle and the commencement of the pick is exceedingly short. In the devices heretofore used it was necessary to wait till the exchange of the bobbin or shuttle was completed, and only then was it possible to commence with the insertion of the needles into the shuttle while in the feeler device according to the present invention the contact can be effected shortly after the current collector 25 bears against the contact rail 24 corresponding to the respective shuttle box compartment, even though the shuttle box may not yet have completed the exchange operation. In addition, the contact lasts till the commencement of the pick while in the devices heretofore known the feeler needles had previously to be removed from the shuttle.

A similar arrangement to that which starts the exchange of bobbin or shuttle, is now also applied for selecting the colors in magazines containing a number of colors. Figs. 7 and 8 show a form of two-color magazine. The shuttles employed according to the color of the bobbin carried, belong to one of two groups A, and B, which correspond to the two bobbin holders A₁ and B₁ of the bobbin magazine 42. The magazine, for instance, may be constructed as a rotary bobbin holder and may be turnably mounted on a spindle 43.

The shuttles of group A differ in no way from those described hereinabove. On the other hand the shuttles of group B in addition to the metal strip 5 carry laterally a metal strip 44 bearing against a spring 45 (Fig. 7) when the shuttle is situated in the shuttle box and which spring is in contact with the feeler device F. The spring 45 is mounted at the shuttle box but is insulated from said shuttle box and the strip 18. Whilst as already described a connection exists between the strip 18, the contact rails 24 of the sliding rail 23, the current collector 25, the magnet 22 and the pole R of the source of current, a second connection is made between 45, the respective contact rail 47 of a second sliding rail 46 in the current collector 48, a second magnet 49 and the pole R of the source of the current. The contact rail 47 is like the rail 24 made in sections.

If a shuttle of the shuttle group B, is situated in the respective shuttle box and its bobbin has run completely empty, two magnets 22 and 49 are fed with current by the contact-effecting feeler device F. Both magnets have a stop or locking device, shown in Fig. 3, comprising at 22 the contact surface 30, the spring 31 and the contact surface 33, and in the magnet 49 (Fig. 7) the contact surface 50, the spring 51 and the contact surface 52. While when the armature is raised, the magnet 22 starts the exchange of bobbin in one of the manners hereinbefore described, the magnet 49 closes the contacts 53 and 56 by means of the two springs 54 and 57 so that the current from the source RST is fed over the contact surfaces 55 and 58 to the motor M (Fig. 4) and causes the latter to rotate.

The motor M drives the bobbin holder 42 by means of a pinion or driver 60 gearing with the toothed wheel 59 (Fig. 8) so that the bobbin group B₁ is brought beneath the hammer or transfrerer 60. A stop 61, which bears against a stationary screw 62 prevents the bobbin holder from turning further than desired and at the same time secures its exact position. When the bobbin has been exchanged after the action of the hammer, the interrupter U may interrupt the current of the source RT whereafter the armatures of both magnets are released and the motor M is stopped. The spring 63 then pulls the bobbin holder back to its original position, whereby the extension 64 abuts against a stationary screw 64.

If, on the other hand, a shuttle of group A₁ is situated in the shuttle box, the bobbin of which is to be exchanged, the magnet 22 alone is excited, the motor M remains at rest and the bobbin magazine remains at rest; so that upon moving the hammer 60 a bobbin of group A₁ is forced into the shuttle.

Obviously, the same effect can be obtained with two circuits or two interrupters as described with reference to Figs. 5 and 6.

For the purpose of moving the rotary bobbin magazine 42 of Fig. 8 it is not absolutely necessary to use a motor; a solenoid can be employed just as well, acting either immediately on the bobbin holder or for instance, causing a stop rod or notched bar to turn, which is then caught by a vertically oscillating knife to alter the position of the magazine, as shown in Fig. 9. In this view 65 represents the circuit-closing spindle or another spindle caused to turn when the exchange of bobbin or shuttle takes place. Said spindle carries a cam 66 which operates the lever arm 68 pivotally mounted on axle 67. Roller 69 mounted on the lever arm 68 bears against the cam 66 under the action of the spring 70. A connecting rod 72 is pivotally connected to the lever arm 68 by means of the pin 71, which connecting rod carries a knife 74 moving in the slot 73. The rotary bobbin holder 42 has an arm 75. At rest said holder, through the action of a spring 76 is pulled with an extension 77 against a stop 78. A stop bar 80 is pivotally mounted on the pin 79 of the arm 75, which stop bar through the action of a spring 81 is pulled against a stop 82 in such a manner that in this position the knife 74 can pass in front of the hook of the stop bar.

Upon each bobbin exchange the spindle 65 is caused to rotate. So long as bobbins of group A₁ are exchanged the bobbin holder 42 remains at rest. If on the other hand, shuttle corresponding to group B₁ is situated in the shuttle box on the side of the feeler, upon rotation of the spindle 65 the magnet 49 is excited at the same time and pushes the stop bar 80 against the knife 74 whereby the wire is caught by the descending knife 74 and the bobbin holder is rotated until a bobbin of group B₁ is brought beneath the hammer.

In four color magazines, for instance, four different groups of shuttles may be used which differ from each other by four different contact strips 83, 84, 85, 86 (Fig. 10) and which are electrically connected to the feeler device F.

The contact strips 83—86 come within reach of the blade springs 87, 88, 89, 90 which are provided on each compartment of the shuttle box and insulated therefrom and connected to corresponding contact rails and sliding rails made of insulating material 91, 92, 93, 94. By means of current

collectors, not shown, upon closing the circuit, current is fed through the feeler device F to one of the four magnets 95, 96, 97, 98, which act on traps 99 of the vertical bobbin holder 100 and open one of said traps in known manner so that one bobbin of the bobbin groups A1, B1, C1, D1 corresponding to the respective shuttle falls beneath the hammer 60 and is thereby forced into the shuttle. The exchange of bobbin is started in known manner by the feeler device F, the sliding rail 24 and the magnet 22, not shown.

Fig. 11 shows an arrangement of a four color magazine which employs rotary holders driven by motors. In this arrangement the pinion or driver 101 of the motor M1 meshes with a toothed segment 103 mounted on the outer bobbin holder 104 whilst the inner bobbin holder 104 is driven by the pinion 105 of the motor M2 meshing with the toothed segment 106. Both rotary holders 102 and 104 are rotatably mounted on a spindle in known manner. The bobbin holder 102 holds the bobbins of groups A1, B1 and the bobbin holder 104 those of group C1, D1. The position of rest of the bobbin holders is ensured by two spring catches 107 and 108 which engage in corresponding plates 109 and 110. The spring catch 107 and the plate 109 ensure the position of the outer rotary holder 102 whilst the inner bobbin holder 104 is held by the gearing catches 108 and the plate 110.

The shuttles of groups A, B, C, D (below) have certain characteristics inasmuch as the shuttles of group A have no lateral contact strips whatsoever, the shuttles of group B have a contact strip 111 above the middle of the shuttle, the shuttles of group C have a contact strip below the middle of the shuttle and the shuttles of group D have a contact strip 113 of double width. Two insulated blade springs 114, 115 are provided on the shuttle box, one of which, 114, touches the contact strips situated above the middle of the shuttle whilst the other, 115, comes into contact with the contact strips below the middle of the shuttle. The contact strips 111, 112, 113 are connected to the feeler device F. For the sake of clearness the shuttles themselves are shown in the drawings as being pulled out to the right. The springs 114, 115 are in contact with corresponding contact pieces provided on the sliding rails 116, 117, whilst the contact pieces of the sliding rail 23 are in contact with the feeler device F by means of the strip 18 described hereinabove and not shown in Fig. 11. From the sliding rail 23 the current passes to the magnet, not shown, which starts the exchange of bobbin, the source of current, R, T, the interrupter U1 and finally to ground. The connections by which current is fed to the sliding rails 116, 117, first pass through the switch W, then likewise the source of current R, T, the interrupter and finally to ground.

Upon each exchange of bobbin the motors M1 and M2 are fed with current in such a manner that always one of them turns to the right or left according to which bobbin group is required by the shuttle. The selection of the motors and their direction of rotation is determined by the switch W which is controlled by the shuttles. Between two phases of the source of current RST a two-pole interrupter U2 is inserted which has for its object to prevent the motors being brought into action before the switch W is in its proper position and to throw the motors M1 and M2 respectively out of gear independently of the interruptor U1.

When one of the motors is started, the bobbin holder rotates until it strikes, with its corresponding extension 118 or 119, against one of the stationary stops 120 or 121. Simultaneously one of the springs 122, 123, or 125 secured to the arm 127 and supported by stationary bolts 128 and 129 is tensioned. For the sake of clearness only one of the arms 118, 119, and 121 as well as the springs 123 and 125 are shown. When the exchange of bobbin is completed and the motors M1 and M2 are respectively switched off, the spring which is under tension pulls the magazine back to its position of rest where it is secured by spring catches 107 and 108 respectively.

Two constructional forms are selected for the working of the switch W. In one of these constructions the motor is controlled by two magnetically energized switches whilst in the other construction the motor is controlled by two magnets combined with a lever or throw-in switch. In Fig. 12 M1 and M2 represent said motors which are connected to the contact surfaces 130, 131, 132 and 133. The phase S of the source of current RST is connected to the contact surface 134 and the phase T to the two contact surfaces 135 and 136. From the sliding rail 116 current is fed to the magnet 137 provided with the known stopping or locking device comprising the contact surface 138 and the spring 139 and from said magnet 137 the current is then fed to the source RT. The sliding rail 117 is connected to the magnet 140 having the locking or stopping device comprising the contact surface 141 and the spring 142 and from there the current is likewise fed to the source. The springs 139 and 142 are grounded. Insulating pieces 143 connect the spring 139 to the springs 144 and 145 as well as the spring 142 to the springs 146 and 147 in such manner that the three springs thus connected make the same movements. The springs 145 and 147 and the springs 144 and 146 are electrically connected.

In the position of rest of the magnets 137, 140 the spring 145 bears against the contact surface 134, the spring 144 against the contact surface 136, the spring 147 against the contact surface 131 and the spring 146 against the contact surface 133. In this position current is fed to the motor M2 in such a manner that the motor rotates, for instance, in the direction I. If the armature of the magnet 140 is now lifted, the spring 146 reaches the contact surface 132 and the spring 147 the contact surface 130, whereby, when the current is switched on, the motor M1 is caused to rotate in the direction I. If the armature of the magnet 137 is raised whilst the magnet 140 is at rest, the spring 144 reaches the contact surface 134 and the spring 145 the contact surface 135. In this way the phases S and T are exchanged and the motor M1 rotates in the direction II. If finally, both magnets 137 and 140 are excited, all springs bear against the upper contact surfaces and the motor M1 rotates in the direction II.

In the constructional forms shown in Figs. 13 and 14, the armatures of the two magnets 137 and 140 are pivotally connected at 149 and 150 to a lever 148. The magnets 137 and 140 have known stop or locking devices comprising the contact surfaces 138, 141 and the springs 139, 142 and are connected to the sliding rails 116 and 117 and have a common connection to the source of current RT (Fig. 13). The lever 148 has the

contact surfaces 151 and 152 connected to the source of current RST. On a plate 153 made of insulating material, are respectively arranged the contact surfaces 154 a, b, c, d and 155a, b, c, d which are connected to the motors M1 and M2 as shown in Fig. 13.

In the position of rest of two magnets 137 and 140 the lever 148 is in the position a and upon switching on the source of current RST the motor M2 is fed with current in such a manner that it turns, for instance in the direction I. If the armature of the magnet 137 is raised, whilst that of the magnet 140 remains at rest, the lever 148 takes up the position b and upon switching on the source of current RST the motor M2 is fed with current in such a manner that it rotates in the direction II, since the contact surfaces 154b and 155b, against which bear the contact surfaces of the lever 151 and 152, exchange the phases of the motor. If the armature of the magnet 140 is raised whilst that of the magnet 137 is at rest, the lever 148 takes up the position c and upon switching on the source of current RST the motor M1 rotates in the direction I. If, finally, the armatures of both magnets 137 and 140 are lifted the lever 148 takes up the position d and upon switching on the source of current RST the motor M1 rotates in the direction II since the contact surfaces 154d and 155d change over the phases of current relative to the contact surfaces 154c and 155c.

The same total effect of both magnets, however, can be obtained by switches as shown in Fig. 15. On the circuit closing spindle 65 or on another shaft caused to rotate, when the exchange of bobbin takes place is provided a cam 66 against which bears the roller 69 of the lever arm 68 pivotally mounted on the stationary pin 67 and subjected to the action of the spring 70. Two connecting rods 156 and 157, which are pivotally connected to the lever arm 68 at 158 and 159, move two knives 162 and 163 guided in the slots 160 and 161. A toothed stop bar 164, which gears with a toothed rod 165 engaging small toothed wheel 166 carried by a stationary pin, is arranged between the knives 162 and 163 in such a manner that it may alternately engage with the knives 162 and 163, as required, whereby the said knives engage in recesses 167 and 168 of the toothed stop bar. The toothed stop bar 164 is guided by a member 169 and its bottom end is forced to the left by means of the spring 170 so that, in the position of rest, the recess 167 embraces the knife 162. The member is, for instance, electrically connected to the armature of the magnet 137. The small toothed wheel 166 gears with a second small toothed wheel 171 which is turnably mounted on a stationary pin and engages in a toothed rod 137 of the toothed stop bar 172 which is similar to the toothed stop bar 164. This stop bar 172 has recesses 174 and 175 which engage with the knives 178 and 179 guided in the slots 176 and 177 respectively. The knife 178 is pivotally connected to the pin 181 by means of the connecting rod 180 mounted on the arm 182 of the inner bobbin holder 104. A similar rod 185 connects the knife 179 to the pin 184 mounted on the arm 185' of the outer rotary bobbin holder 102. The lower end of the toothed stop bar 172 is guided by members 183 which is forced to the right hand side by means of a spring 184 and electrically connected to the armature of the magnet 140 in such a manner that, when the magnet is at rest, the recesses 174 of the stop bar 172 embrace the knife 178. The bobbin holders are made in two

parts and contain bobbins of the groups A1, B1, C1, and D1, which, as the case may be, are pushed in the shuttles A, B, C, D. These shuttles have the same characteristics as those shown in Fig. 11. Upon every exchange of bobbin the circuit closing shaft 65 is caused to rotate. According to whether none or both or one or the other of the two magnets 137 and 140 is or are excited the toothed stop bar 164 either engages with the knife 162 or the knife 163 and the toothed stop bar 172 engages either with the knife 178 or 179. Upon moving the lever arm 68 by means of the cam 66 either the inner or the outer bobbin holder is displaced in a different direction so that the bobbin group required for the time being is brought beneath the hammer 60 and may be pushed in the shuttle.

Having now described the invention what is claimed as new and desired to be secured by Letters Patent is:

1. An electric weft-selecting mechanism for an automatic multicolor bobbin changing loom employing a plurality of active weft bobbins of differing weft-characteristics and a plurality of shuttles embodying weft feelers and each shuttle carrying a bobbin of weft-characteristic differing from those of the other shuttles, comprising a rotatable magazine provided with separate compartments, one for each group of bobbins of like weft-characteristics, magazine positioning means including electric magazine driving and stop means arranged to selectively position the magazine in any one of a plurality of predetermined positions wherein a bobbin of selected weft-characteristics may be transferred from the magazine to an active exhausted shuttle thereunder, electric circuit means electrically connected with the magazine driving means and including said weft feelers, shuttle-carried contact means differently positioned on the several shuttles, shuttle-box carried contact means arranged and positioned for cooperation with the shuttle-carried contact means, a source of electric energy and a loom driven circuit timing means, said several means being so constructed and arranged that consequent upon closure by a feeler of a circuit including certain of said shuttle and shuttle box contacts, the timer and magazine driving means, the magazine is positioned with a bobbin of proper weft characteristic positioned above the exhausted shuttle ready for transfer to the latter.

2. An electric weft-selecting device for automatic weft-replenishing looms employing shuttles embodying weft feelers, transfer hammer, drop boxes and a bobbin in each shuttle, comprising a weft feeler, circuit and other circuits for actuating the replenishing mechanism, magazine actuating means, a contact for closing said weft feeler circuit, additional contacts on at least some shuttles for closing other circuits for selectively controlling the magazine actuating means, said additional contacts being so arranged to the weft feeler circuit that, by the exhausted bobbin through a weft feeler, none of the selecting circuits is closed, during normal operation of said device and one of which circuits is closed for replenishing action depending upon to which group of the shuttles employed the shuttle containing the exhausted bobbin belongs, whereby on initiation of the bobbin-changing operation there results the positioning under said transfer hammer of a new bobbin of corresponding color or character to the exhausted one, circuit closing rails arranged on and moving with said drop boxes being used,

and stationary current collectors co-operating with said rails.

3. Electric weft-selecting device according to claim 2 including an electric motor for effecting the positioning of the required bobbin under said transfer hammer on actuation of the magazine and transfer mechanism.

4. Electric weft-selecting device according to claim 2 and having weft feeler box embodying feelers, a crank shaft and a change shaft including 10 an interrupter on said change shaft and synchro-

nising with said crank shaft of the weft-replenishing loom, said feelers and said interrupter for closing the selecting circuit energizable by the shuttles, and a holding device for maintaining said interrupter closed independent of the opening of the feelers and of said crank shaft until said interrupter set in motion by initiation of the replenishing operation breaks the circuit of said holding device.
